UNITED STATES PATENT OFFICE.

REGINALD LUCKORK MUIR, OF NEW YORK, N. Y.

WARDROBE SET.

1,117,593.

Specification of Letters Patent.

Patented Nov. 17, 1914.

Application filed April 4, 1912. Serial No. 688,480.

To all whom it may concern:

Be it known that I, REGINALD L. MUIR, a citizen of the United States, residing at New York, county and State of New York, have 5 invented certain new and useful Improvements in Wardrobe Sets, of which the following is a full, clear, and exact description.

This invention relates to "wardrobe sets," that is, devices for hanging garments in a 10 wardrobe or closet, and its chief object is to provide a set which when used in connection with any ordinary closet hook will enable a half-dozen or more garments to be suspended therefrom instead of but two, or 15 at most three, as heretofore has been the case.

A further object is to provide a set whose 20 various parts are collapsible into compact form, so that it can be conveniently carried by travelers.

A further object is to provide a set which can be made entirely of wire, bent to shape, thereby making the device inexpensive to manufacture.

25 To these and other ends the invention consists in the novel features of construction and combinations of elements hereinafter described, and more particularly set forth in the appended claims.

30 A convenient and effective form of the invention is illustrated in the accompanying drawings, in which the device is shown in perspective.

The body of the garment support, on 35 which the coat is hung, is formed of a single piece of stiff wire, provided at one end with a suspending hook 10. Below the hook the wire has a straight portion 11, at the bottom of which the wire is bent in an obtuse 40 angle to form an inclined portion 12. At the outer end of the inclined portion the wire is coiled helically for one and a half turns, forming the circular loop 13, and then extends horizontally to a similar loop 14 45 at the opposite side. From the latter loop the wire extends up to and is bent around the stem 10, forming an inclined portion 15 which makes with the stem the same angle as does the other inclined portion 12. Between the vertical end-loops 13, 14, the horizontal portion 16 is provided with two horizontal loops 17, 18, to one of which is pivoted a wire clamping member 19 by means 50 of a loop 20 formed by bending the end of the wire. The other end of the clamping

member is bent into a hook 21 to engage the loop 18. The bottom of a pair of trousers, or the band of a skirt, can be clamped between members 16, 19, so as to hang therefrom without creases or folds.

On the inclined portions 12, 15, a pair of shoulder supports 22, 23 for the coat are provided, each consisting of a single piece of wire bent to shape, as shown, and rotatably mounted on the shoulder portions 12, 15, 60 by means of loops 24, 25. When the device is in use the shoulder supports are horizontal, as shown, but when the device is to be stored or carried they are turned through an angle of ninety degrees into the plane of 70 the wires 12, 15, 19.

The suspending device is also made of wire, and comprises a back made of a single piece of wire, bent to shape and having upper and lower oppositely inclined portions 75 26, 27, 28, 29, with end loops 30 and upper and lower loops 31, 32 at the center and in vertical alinement with each other.

33 designates a suspending ring formed on the end of a wire which has a straight portion or stem 34 at the lower end of which it is bent sharply toward the rear. At the loop 31 the wire is bent downwardly and passes through the two loops 31, 32, forming a pivot 34a. Below the latter the wire is bent 80 forwardly to provide a bar 35 on which the garment hangers may be suspended. At the point 36 the wire is bent upwardly and forwardly, then forms a loop 37 and extends from the latter to the bend at the base of the stem 34 to which it is tightly secured by the loop or bend 38. Pivoted on the inner or rear portion of the loop 37 by means of loops 39, 40, are two wire stays 41, 42, provided at their rear ends with hooks 43, 44, 85 tightly but releasably engaging the inner portions of the back loops 30. These stays serve to maintain the forwardly extending hanger in position at right angles to the back when the device is in use.

100 The suspending device just described is designed to be hung by the ring 33 upon the usual closet hook, and when it is thus suspended the back portion bears against the closet wall and keeps the bar 35 horizontal, while the stays 41, 42, keep it perpendicular to the wall. Any number of garment hangers can be suspended on the bar 35, depending upon the length of the latter. Thus a bar about six inches long will hold 110

six hangers, whereas the closet hook on which the device is hung will hold only three garments at most.

When the suspending device is to be collapsed for storing or carrying the stays 41, 42, are disengaged from the loops 30, whereupon the parts can all be folded flat upon the back portion.

As will be seen from the foregoing description the entire outfit or "set" can be folded into most compact form, occupying a space not much thicker than the wire itself. When arranged for use it is strong enough for the heaviest garments, and permits the garments to hang in natural folds without creasing or wrinkling. It can also be manufactured at low cost even when made by hand, as the manipulations are of the utmost simplicity.

It is to be understood that the invention is not limited to the precise details of construction herein specifically illustrated and described, but can be embodied in other forms without departure from its proper spirit and scope as defined by the following claims.

I claim:

1. In a wardrobe set, a suspending device comprising a back formed of wire bent to

shape and provided with aligned upper and lower loops, a frame having a vertical portion pivotally mounted in said loops, and having a suspending bar at the bottom and means at the top for suspension on a closet hook, and a pair of stays releasably connecting the forward portion of the frame to the back whereby to hold the frame in forwardly extending position with said suspending bar substantially horizontal.

2. In a wardrobe set, a suspending device comprising a back formed of wire bent to shape and having end loops and aligned upper and lower loops, a wire frame pivotally mounted in the upper and lower loops, having a loop at its forward end and a suspending bar below said forward loop and extending rearwardly therefrom, and a pair of stays formed of wire looped in said forward loop so as to swing thereon and provided with hooks adapted to releasably engage the end loops on the back.

In testimony whereof I affix my signature in the presence of two subscribing witnesses:

REGINALD LUCKORK MUIR.
